Wenfield Maudie Brooks

UNITED STATES PATENT OFFICE.

WINFRED MUDGE BROOKS, OF SOUTH ORANGE, NEW JERSEY.

SEALING MEANS.

Application filed June 13, 1921. Serial No. 477,006.

To all whom it may concern:

Be it known that I, WINFRED M. BROOKS, a citizen of the United States, and a resident of South Orange, in the county of Essex and State of New Jersey, have invented certain new and useful Improvements in Sealing Means, of which the following is a specification.

This invention relates generally to wire seals of the character employing a soft metal sealing element and a wire element, one end of which is imbedded in the sealing element and the other end of which is bent back upon itself and introduced into an opening in the sealing element.

Great difficulty has heretofore been experienced in obtaining in the wire element requisite strength combined with necessary pliability; and the main object and feature of this invention is to increase the strength and flexibility of the wire element associated with the sealing medium without unduly increasing the diameter of the wire element.

In the accompanying drawing the invention is disclosed in a concrete and preferred form in which—

Figure 1 is a general view in plan of a seal embodying the invention;

Figure 2 is a detail view of a portion of the wire element used; and

Figure 3 is a cross-sectional view on the line 3—3 of Figure 2.

1 indicates the sealing medium, which may be a piece of lead or other soft and compressible material, and 2 indicates the wire element, one end 3 of which is embedded in the sealing element and the other end 4 of which passes through a slot in the sealing element in a manner well understood, the wire being bent back upon itself, as shown, to form a loop.

I have found that, by making the wire element in the form of a strand composed of a plurality of very fine wires 5, the strength of the wire element may be materially increased without materially increasing its diameter.

It appeared, however, that the twisted wire strand was not nearly so flexible and pliable as a wire element made of a single wire, but I then found that by crimping the twisted strand in the manner indicated in Figure 2 that additional and requisite pliability would be afforded without lessening the strength of the wire element.

I claim:

A wire seal comprising: a soft metal sealing element, and a crimped wire strand associated with said sealing element by being bent back upon itself, said strand consisting of a plurality of wires twisted together.

Signed at New York city, in the borough of Manhattan, county and State of New York, this 9th day of June, 1921.

WINFRED MUDGE BROOKS.
